GRINDING MILL

Ervin G. Bailey, Easton, Pa., and Perry R. Cassidy, Short Hills, and Ralph M. Hardgrove, Westfield, N. J., assignors to Fuller Lehigh Company, Fullerton, Pa., a corporation of Delaware

Application June 5, 1929, Serial No. 368,506
Renewed July 25, 1934

23 Claims. (Cl. 83—45)

This invention relates to a grinding mill of the ball type in which the fine particles of the ground material are removed from the mill by an air current. Provision is also made by means of which coarse particles of material may be separated from the air current and returned to be reground. The invention is especially applicable for grinding or pulverizing coal, but it is not restricted to this particular use.

10 The invention will be understood from the description in connection with the accompanying drawings in which Fig. 1 is a vertical section through an illustrative embodiment of the invention; Fig. 2 is a section along the line 2—2 of Fig. 1; Fig. 3 is a section along the line 3—3 of Fig. 1; Fig. 4 is a section along the line 4—4 of Fig. 1; and Fig. 5 is a section along the line 5—5 of Fig. 1.

In the drawings reference character 1 indicates 20 a base to which the bottom part 2 of the machine may be bolted by means of the bolts 3. A flat thick disc 4 is located in the lower portion of the hollow bottom 2 of the machine and is provided with a central opening 5. A ball ring 6 adapted to withstand thrust is mounted upon the disc 4.

The casing 7 of the machine extends upwardly 30 from the bottom portion 2 and encloses the grinding parts of the machine. The lower portion of the casing 7 is made outwardly flaring, as indicated at 8, to provide the outer wall of an annular air space 9 into which an air inlet 10 leads. An air compressor or fan may force the air through the mill or a suction fan may draw the air through it.

An air tight wall 11 extends from the outside 40 of the ring 6 to the upper portion of the flaring wall 8 to provide the other side or wall of the annular air space 9. A plurality of air ports 12 extend through the ring 6 to permit air to pass therethrough from the space 9.

A deflector 13 approximately as long as the ring 6 and of smaller diameter than the inside 45 diameter of this ring is connected to the disc 4 so as to leave an annular space 14 between it and the ring 6. A ball race 16 for the grinding balls 17 is provided along the upper edge of the ring 6 and serves as a grinding surface.

50 A rotatable driving and grinding ring 18 is located above the row of balls 17 and is provided with ball races along its lower and upper edges. A row of balls 19 is provided above the ring 18, these balls being preferably larger than the balls 17. A pressure ring 20 of smaller diameter than

the casing 7 is located above the balls 19 to contact with the same.

A sheet metal ring 22 is attached to the inside of the wall 11 approximately at the level of the upper side of the ring 18. This ring 22 is L-shaped in cross section and may be connected to the wall 11 in any convenient manner, but preferably by means of bolts 22' through vertically disposed slots to permit the ring 22 to be adjusted up and down. The inside of this ring is slightly 10 larger than the outside diameter of the driving ring 18 to leave an annular space 23 between the ring 18 and the ring 22. The size of the opening 23 can be varied by adjusting the position of the ring 22 up and down with respect to the ring 18 15 by means of the bolts 24 extending through screw threaded holes in the support 25.

A vertical shaft 26 extends through the opening 5 in the disc 4 and is driven by means of a motor 27 through reduction gearing. A hub 28 20 is provided on the shaft 26 and a driving member 29 for the ring 18 is attached to the hub 28. The driving member 29 is provided with arms 29' that extend into vertically disposed slots between lugs 30 along the inside surface of the ring 18, 25 so that the ring 18 is permitted to move up and down with respect to the driving member 29. A screen 31 approximately in the form of a truncated cone extends upwardly from the inner edge of the ring 18 along the inside of the row of balls 30 31. This screen is provided with slots 31'.

A conical deflector 32 is attached to the driving member 29 and is provided with a flange 33 at its lower end and fan blades 34 above the flange 33 in position to create a current of air that impinges against the row of balls 17.

A cylindrical housing 35 extends from the upper edge of the screen 31 to a point some distance above the upper edge of the ring 20 leaving an annular space 36 between screen and housing. 40 The circumferential wall of the housing 35 is provided with openings over which wire screens 37 extend.

The ring 20 is prevented from revolving by means of lugs 38 along the inside surface of the casing 7, which lugs contact with lugs 39 on the outside of the ring 20 or project into vertically disposed slots along the outside of this ring. Contact pieces 40 with rounded ends are provided along the upper surface of the pressure ring 20 45 for the lower ends of plungers 41 that may be pressed downwardly in any convenient manner, as for example, by means of springs. Each plunger 41 passes through a stuffing box 42. The stuffing boxes are located in inset portions of the 50 55

casing 7, as most clearly indicated in Fig. 2. The upper end of the plunger 41 is connected to a piston 43 in the cylinder 44 attached to the casing 7. Compression springs 45 are interposed between the piston 43 and the disc 46. The disc 46 is adjustable by means of the screw 47 to vary the compression of the springs 44. Stops 48 that may be adjustable along the inside of the casing 7 may be provided to limit the downward movement of the plungers 41.

A feed chute 50 extends through the closed top of the upper end of the casing 7 into position to feed material between the housing 35 and ring 20. A cylindrical outlet 51 is provided at the top 15 of the machine and a conically shaped classifier 52 is located below the outlet 51 with its upper edge extending higher than the lower edge of the outlet 51. The lower small end of the classifier 52 is left open, as indicated at 53. An opening 20 54, which is normally closed by means of a door, is provided in the side of the casing 7 for access to the inside.

The operation is as follows:

The material to be ground is fed through the chute 50 and passes down through the annular space between the inside of the stationary ring 20 and the housing 35. The material is then ground to some extent by means of the large balls 19 that are carried around by the rotating ring 18. Some of the fine material is picked up by a current of upwardly ascending air. The particles ground by the balls 19 pass through the annular space 23 between the rings 18 and 22 to fill the lower portion of the space along the inside of the converging portion of the wall 11. The arrangement of the ring 22 relative to the grinding ring 18 provides a regulable restriction controlling the flow of material between the upper and lower grinding stages, which is disclosed and claimed in our 40 copending application Serial No. 390,698, filed September 6, 1929. The material is further ground by means of the row of balls 17.

Air under pressure passes through the inlet 10 into the annular space 9 and thence through the ports 12 and upwardly through the annular space 45 between the wall 13 and the inside of the ring 6. The upwardly rising sheet of air picks up the ground material that is passed through the row of balls 17 and the fans 34 also help to pick up 50 the fine particles. The air carrying the fine particles passes upwardly through the inside of the ring 18 and a small portion passes through slots 31 and picks up some fine coal from balls 19. The mixture of air and pulverized material then passes 55 through the screens 37 or through annular space 36 or both. The air and fine particles then pass upwardly and around the upper edge of the cone 52 and thence under the lower edge of the cylindrical outlet 51 causing the coarse particles to be thrown out and pass downwardly through the 60 opening 53 onto the top of the housing 35 from which it is thrown off and passes downwardly with the incoming material to be again ground. The air and fine particles pass out through the outlet 51 to a place of use or storage.

By providing pressure applying means to the top of the pressure ring 20, the capacity of the machine is automatically increased by feeding material more rapidly. This occurs because the 70 layers of material that are being ground by the balls raise the rings 18 and 20, thus compressing the springs and causing them to exert greater pressure upon the grinding elements. At light loads the ring 20 descends far enough to permit the plungers 41 to rest upon the stops 48, thus de-

creasing the amount of power that would be required at light loads if pressure were exerted upon the ring 20.

By having the balls in the upper row 19 of larger size than the balls in the lower row 17, the coarse or rough grinding of the material is accomplished by the first row of balls 19 and the smaller balls 17 finish the grinding. Also balls that have been worn down a certain amount in the upper ring are still good for further service in the lower ring 10 as the grinding action is such that the balls remain spherical.

While in accordance with the provisions of the statutes we have illustrated and described herein the best form of our invention known to us, those skilled in the art will understand that changes may be made in the form of the apparatus and character of the carrier medium disclosed without departing from the spirit of the invention covered by our claims, and that certain features of our invention may sometimes be used without a corresponding use of other features. In our claims, the term "air" is used generically to cover any gaseous carrier medium suitable for removing pulverized material in the manner described.

25

We claim:

1. In a grinding mill, a plurality of circular rows of grinding elements, means for feeding material to be ground to the outside of one of said rows, and means to cause a current of air to pass 30 upwardly in proximity to said grinding elements along the inside of said rows.

2. In a grinding mill, a plurality of circular rows of grinding elements, means for feeding material to be ground to the outside of one of 35 said rows, and means to cause a current of air to pass upwardly in an annular band in proximity to said grinding elements along the inside of said rows.

3. In a grinding mill, a plurality of circular rows of grinding elements, means for feeding material to be ground to the outside of one of said rows, means to withdraw ground material along the inside of said rows, and means to return coarse particles to said grinding elements.

4. In a grinding mill, a plurality of circular rows of grinding elements, means for feeding material to be ground to the outside of one of said rows, a screen, and means to withdraw ground material along the inside of said rows, 50 said screen being located in the path of the material being withdrawn.

5. An air-swept grinding mill comprising a substantially air-tight casing having an inlet for material to be ground and an outlet for ground material in the upper part thereof, a plurality of vertically spaced grinding rings in said casing, upper and lower circular rows of rolling grinding elements positioned between different pairs of grinding rings and cooperating therewith to form upper and lower grinding stages, each receiving material to be ground at one side of said row of elements and discharging ground material at the other side, and means for directing an annular stream of air upwardly through said casing adjacent to and mainly past the discharge side of one of said rows of elements and conveying the material ground thereby to said casing outlet.

6. An air-swept grinding mill comprising a substantially air-tight casing having an inlet for material to be ground and an outlet for ground material in the upper part thereof, a plurality of vertically spaced grinding rings in said casing, upper and lower circular rows of rolling grinding elements positioned between different pairs 70

of grinding rings and cooperating therewith to form successive grinding stages, each receiving material to be ground at one side of said row of elements and discharging ground material at the other side, and means for directing an annular stream of air upwardly through said casing adjacent to and mainly past the discharge side of said lower row of elements and conveying the material ground thereby to said casing outlet.

10. 7. An air-swept grinding mill comprising a substantially air-tight casing having an inlet for material to be ground and an outlet for ground material in the upper part thereof, a plurality of vertically spaced grinding rings in said casing, upper and lower circular rows of rolling grinding elements positioned between different pairs of grinding rings and cooperating therewith to form a plurality of grinding stages, each receiving material to be ground at one side of said row of elements and discharging ground material at the other side, means for directing an annular stream of air upwardly through said casing adjacent to and mainly past the discharge side of one of said rows of elements and conveying the material ground thereby to said casing outlet, and means in the path of flow of said air stream for separating out coarse material and returning the separated material to the feed side of one of said grinding stages.

30. 8. An air-swept grinding mill comprising a substantially air-tight casing having an inlet for material to be ground and an outlet for ground material in the upper part thereof, a plurality of vertically spaced grinding rings in said casing, a circular row of rolling grinding elements positioned between said grinding rings and cooperating therewith to form a grinding stage receiving material to be ground at the outer side of said row of elements and discharging ground material at the inner side, and means for directing an annular stream of air upwardly through said casing adjacent to and mainly past the inner side of said row of elements and conveying the material discharged therefrom to said casing outlet.

45. 9. An air-swept grinding mill comprising a substantially air-tight casing having an inlet for material to be ground and an outlet for ground material in the upper part thereof, a plurality of vertically spaced grinding rings in said casing, a circular row of rolling grinding elements positioned between said grinding rings and cooperating therewith to form a grinding stage receiving material to be ground at one side of said row of elements and discharging ground material at the other side, means for directing an annular stream of air upwardly through said casing adjacent to and mainly past the discharge side of said row of elements and conveying the material ground thereby to said casing outlet, and means in the path of flow of said air stream for separating out coarse material and returning the separated material to the feed side of said grinding stage.

60. 10. A grinding mill comprising a casing having an inlet for material to be ground and an outlet for ground material, a grinding ring in said casing, a circular row of rolling grinding elements supported on said grinding ring and cooperating therewith to form a grinding stage, means for exerting pressure between said grinding elements and said ring including a floating pressure ring supported on said grinding elements and regulable resilient means acting downwardly on said pressure ring to superpose a grinding pressure thereon, and means for rendering said resilient

means ineffective at predetermined positions of said floating pressure ring.

11. In a grinding mill, a plurality of rows of rotating grinding elements, means for feeding material to one row of said elements in one direction and to another row in the opposite direction, and means to cause an air current to pass upwardly through the inside of said rows of elements.

10. 12. In a grinding mill, a plurality of rows of rotating grinding elements, means to cause material to pass from the inside to the outside of one row of said elements and from the outside to the inside of another row of balls, and means to cause an air current to pass upwardly through the inside of said rows of elements.

15. 13. In a grinding mill, a plurality of rows of rotating grinding elements, means comprising a conically shaped plate to cause material to pass from the inside to the outside of one row of said elements and from the outside to the inside of another row of said elements, and means to cause an air current to pass upwardly through the inside of said rows of elements.

20. 14. In a grinding mill, a plurality of rows of rotating grinding elements, means comprising a conically shaped plate to cause material to pass from the inside to the outside of one row of said elements and from the outside to the inside of another row of said elements, and means to cause an air current to pass upwardly through the inside of said rows of elements.

25. 15. An air-swept grinding mill comprising a casing having an outlet for ground material in the upper part thereof and enclosing vertically spaced upper, intermediate and lower grinding rings, circular rows of rolling grinding elements positioned between said upper and intermediate and said intermediate and lower grinding rings

30. and cooperating therewith to form an upper grinding stage having an outward flow of material therethrough and a lower grinding stage receiving material from said upper stage and having an inward flow of material therethrough, a drive shaft arranged axially of said grinding rings, means forming a rotary drive connection between said shaft and intermediate grinding ring, means preventing rotation of said upper and lower grinding rings, means for delivering material to be ground to the inner side of said upper row of elements, an air box at the lower part of said casing, and means for directing a stream of air from said box upwardly through said casing adjacent to and mainly past the inner side of said lower row of elements and conveying material discharged therefrom towards said casing outlet.

35. 16. An air-swept grinding mill comprising a casing having an outlet for ground material in the upper part thereof and enclosing vertically spaced upper, intermediate and lower grinding rings, circular rows of rolling grinding elements positioned between said upper and intermediate and said intermediate and lower grinding rings and cooperating therewith to form an upper grinding stage having an outward flow of material therethrough and a lower grinding stage receiving material from said upper stage and having an inward flow of material therethrough, a drive shaft arranged axially of said grinding rings, means forming a rotary drive connection between said shaft and intermediate grinding ring, means preventing rotation of said upper and lower grinding rings, means for delivering material to be ground to the inner side of said

- upper row of elements, an air box at the lower part of said casing, air passages below said lower grinding ring connecting said air box to the inner side of said lower row of elements, and means 5 for directing a stream of air from said air box through said passages and thence upwardly through said casing adjacent to and mainly past the inner side of said lower row of elements and conveying material discharged therefrom towards 10 said casing outlet.
17. An air-swept grinding mill comprising a casing having an outlet for ground material in the upper part thereof and enclosing vertically spaced upper, intermediate and lower grinding 15 rings, circular rows of rolling grinding elements positioned between said upper and intermediate and said intermediate and lower grinding rings and cooperating therewith to form an upper grinding stage having an outward flow of material therethrough and a lower grinding stage receiving material from said upper stage and having an inward flow of material therethrough, a drive shaft arranged axially of said grinding rings, means forming a rotary drive connection 20 between said shaft and intermediate grinding ring, means preventing rotation of said upper and lower grinding rings, means for delivering material to be ground to the inner side of said upper row of elements, an air box at the lower 25 part of said casing, means for directing an annular stream of air from said air box upwardly through said casing adjacent to and mainly past the inner side of said lower row of elements and conveying material discharged therefrom towards 30 said casing outlet, and means in the path of flow of said air stream for separating out coarse material and returning the separated material to the inner 35 side of said upper row of elements.
18. An air-swept grinding mill comprising a casing having an outlet for ground material in the upper part thereof and enclosing vertically spaced upper, intermediate and lower grinding rings, circular rows of rolling grinding elements positioned between said upper and intermediate and said intermediate and lower grinding rings and cooperating therewith to form an upper 40 grinding stage having an outward flow of material therethrough and a lower grinding stage receiving material from said upper stage and having an inward flow of material therethrough, a drive shaft arranged axially of said grinding rings, means forming a rotary drive connection between said shaft and intermediate grinding ring, means preventing rotation of said upper and lower grinding rings, means for delivering material to be ground to the inner side of said upper row of elements, an air box at the lower 45 part of said casing, means for directing an annular stream of air from said air box upwardly through said casing adjacent to and mainly past the inner side of said lower row of elements and conveying material discharged therefrom towards 50 said casing outlet, and means in the path of flow of said air stream for causing the air stream to pass through the stream of material being delivered to the inner side of said upper row of elements.
19. An air-swept grinding mill comprising a substantially air-tight casing having an outlet for ground material in the upper part thereof and enclosing vertically spaced upper, intermediate and lower grinding rings, circular rows of rolling grinding elements positioned between said upper and intermediate and said intermediate and lower grinding rings and cooperating 55
- therewith to form an upper grinding stage having an outward flow of material therethrough and a lower grinding stage receiving material from said upper stage and having an inward flow of material therethrough, a drive shaft arranged axially of said grinding rings, means forming a rotary drive connection between said shaft and intermediate grinding ring, means preventing rotation of said upper and lower grinding rings, means for delivering material to be ground to the inner side of said upper row of elements, an annular air box surrounding said casing, air passages below said lower grinding ring connecting said air box to the inner side of said lower row of elements, means for directing an annular stream of air from said air box through said passages and thence upwardly through said casing adjacent to and mainly past the inner side of said lower row of elements and conveying the material discharged therefrom towards said casing outlet, and means in the path of flow of said air stream for separating out coarse material and returning the separated material to the inner side of said upper row of elements.
20. An air-swept grinding mill comprising a substantially air-tight casing having an inlet for material to be ground and an outlet for ground material in the upper part thereof, a plurality of vertically spaced grinding rings in said casing including a rotary upper grinding ring and a non-rotary lower grinding ring, a circular row of rolling grinding elements positioned between said grinding rings and cooperating therewith to form a grinding stage receiving material to be ground at the outer side of said row of elements and discharging ground material at the inner side, drive means having a drive connection with said upper ring, resilient means for applying a grinding pressure between said grinding rings and row of elements, and means for directing an annular stream of air upwardly through said casing adjacent to and mainly past the inner side of said row of elements and conveying the material discharged therefrom to said casing outlet.
21. An air-swept grinding mill comprising an annular air box, a substantially air-tight casing extending above said air box and having an inlet for material to be ground and an outlet for ground material in the upper part thereof, a plurality of vertically spaced grinding rings in said casing, a circular row of rolling grinding elements positioned between said grinding rings and cooperating therewith to form a grinding stage receiving material to be ground at the outer side of said row of elements and discharging ground material at the inner side, and means for directing an annular stream of air from said air box below said lower ring and thence upwardly through said casing adjacent to and mainly past the inner side of said row of elements and conveying the material discharged therefrom to said casing outlet.
22. An air-swept grinding mill comprising an annular air box, a substantially air-tight casing extending above said air box and having an inlet for material to be ground and an outlet for ground material in the upper part thereof, a plurality of vertically spaced grinding rings in said casing including a rotary upper grinding ring and a non-rotary lower grinding ring, a circular row of rolling grinding elements positioned between said grinding rings and cooperating therewith to form a grinding stage receiving material to be ground at the outer side of said row of elements and discharging ground

material at the inner side, drive means having a drive connection with said upper ring, resilient means for applying a grinding pressure between said grinding rings and row of elements, and 5 means for directing an annular stream of air from said air box below said lower ring and thence upwardly through said casing adjacent to and mainly past the inner side of said row of elements and conveying the material dis- 10 charged therefrom to said casing outlet.

23. An air-swept grinding mill comprising an annular air box, a substantially air-tight casing extending above said air box and having an inlet for material to be ground and an outlet for 15 ground material in the upper part thereof, a plurality of vertically spaced grinding rings in said casing including a rotary upper grinding ring and a non-rotary lower grinding ring, a circular row of rolling grinding elements positioned between said grinding rings and cooper- 20

ating therewith to form a grinding stage receiving material to be ground at the outer side of said row of elements and discharging ground material at the inner side, a drive shaft extending upwardly axially of said row of elements and having a drive connection with said upper ring, resilient means for applying a grinding pressure between said grinding rings and row of elements, means for directing an annular stream of air from said air box below said lower ring and 10 thence upwardly through said casing adjacent to and mainly past the inner side of said row of elements and conveying the material discharged therefrom to said casing outlet, and means in the path of flow of said air stream for separating out 15 coarse material for return to the outer side of said grinding stage. 5
